UNITED STATES PATENT OFFICE.

ADOLPH D. BREDER, OF VERONA, MISSOURI.

INCUBATOR.

1,202,661.

Specification of Letters Patent.

Patented Oct. 24, 1916.

Application filed September 23, 1912. Serial No. 721,938.

To all whom it may concern:

Be it known that I, ADOLPH D. BREDER, a citizen of the United States, residing at Verona, in the county of Lawrence, State of Missouri, have invented certain new and useful Improvements in Incubators; and I do hereby declare the following to be a full, clear, and exact description of the invention, such as will enable others skilled in the art 10 to which it appertains to make and use the same.

This invention relates to new and useful improvements in incubators.

The principal object of the invention is 15 to provide a means for automatically regulating the temperature of incubators.

Another object of the invention is to provide a heat regulating means for the purpose set forth which may be easily adjusted and 20 thereby regulate the temperature of the incubator to a nicety.

A further object of the invention is to provide a heat regulating means for the purpose set forth which is extremely simple 25 in construction, it being composed of a minimum number of parts and is therefore cheap to manufacture.

With these and other objects in view, the 30 invention consists in the construction and novel combination of parts hereinafter fully described, illustrated in the accompanying drawings and pointed out in the claims hereto appended; it being understood that various changes in the form, proportion, 35 size and minor details of construction within the scope of the claims may be resorted to without departing from the spirit or sacrificing any of the advantages of the invention.

40 In the drawings: Figure 1 is a perspective view of my improved regulating means, the air conveying pipes being broken away to better show the operation thereof, Fig. 2 is a vertical longitudinal sectional view 45 taken through the heating drum, Fig. 3 is a vertical transverse sectional view taken through the incubator, and Fig. 4 is a detail horizontal sectional view through a portion of the incubator and the heating drum.

50 Like reference numerals designate corresponding parts in all the figures of the drawings.

55 Referring to the drawings, an incubator of any suitable type is indicated as a whole by the reference numeral 10. Supported upon a bracket 11 which depends from the

incubator is an oil burner 12 of any suitable type. The heat from this burner passes upwardly through an air conducting pipe 13, and connected to the upper end thereof is a 60 flue 14 which is preferably smaller than the pipe 13, and which in fact, forms a continuation thereof. A laterally directed air pipe 15 communicates with the incubator 10 and with the upper end of the pipe 13 and serves to convey hot air from said pipe into the incubator. An air escape 16 communicates with the incubator 10 and with the flue 14. Disposed around the pipe 13 and flue 14 is a 65 drum 17 of any suitable construction.

70 A transverse rock shaft 18 is suitably journaled in the drum 17 exterior of the flue 14 and pipe 13, and fixed on this shaft is a valve 19 which is adapted to alternately close the flue 14 and the air pipe 15 so as to 75 either direct the hot air from the burner 12 outwardly through the flue 14 or into the incubator 10 through the pipe 15.

In order to actuate the valve 19 when the 80 temperature within the incubator varies, there is provided a bracket 20 which is suitably secured within the incubator 10 and supports a thermostat 21 of the expanding type, the upper plate thereof carrying a seat 22. Secured to the bracket 20 is a bracket 85 arm 23 which terminates at its inner end directly above the seat 22. Journaled in the free end of the arm 23 at a point to one side of the seat 22 is a rock shaft 24, one end thereof extending forwardly through an opening 25 formed in the wall of the incubator 10 adjacent the drum 17. Fixed on the inner end of the shaft 24 is a U-shaped 90 rocker arm 26, and journaled in the legs of this rocker arm is a transverse pivot pin 27 95 having a threaded opening formed therein. A stand rod 28 has its lower end threaded for engagement with the opening formed in the pin 27, and the lower end of this rod bears upon the seat 22 of the thermostat 21.

The upper end of the rod 28 passes through 100 an opening 29 formed in the top of the incubator 10 and extends through an opening 30 formed in a plate 31 which is secured to said top. The upper end of the rod 28 terminates 105 in a head 32, and in order to lock the rod 28 from downward movement when the thermostat contracts, there is provided a sliding plate 33 which is centrally slotted, as at 34, for receiving the rod 28. This plate is disposed under the head 32 and operates between opposed flanges 35-35 formed on the 110

plate 31. It will thus be observed that when the thermostat 21 expands, the rod 28 will be elevated, and through the medium of the pin 27, the U-shaped rocker arm 26 will 5 cause the rock shaft 24 to be oscillated.

A balance lever 36 is provided intermediate its ends with a weight 37 which is formed with a transverse opening for receiving the rock shaft 24, said lever being 10 loosely mounted upon said rock shaft. The rock shaft 24 extends beyond the weight 37, and connected to this end is the end of the long arm of a J-shaped finger 38. The end of the short arm of the finger is disposed 15 below the end of the weight 37 opposite the rock shaft 24, and is held in adjusted position with respect to the lever 36 by means of an adjusting screw 39 which operates through the weight 37. It will thus be ob- 20 served that by means of the screw 39 and the finger 38, the position of the balance lever 36 with respect to the axis of the rock shaft 24 may be regulated.

Secured to one end of the rock shaft 18 is a 25 block 40, and adjustably mounted in said block by means of a set screw 41 is a rocker arm 42, one end thereof being suitably connected to a link 43 which is connected at its other end to the adjacent end of the balance lever 30 36. It will thus be observed that as the lever 36 is oscillated through the medium of the rock shaft 24 and finger 38, the link 43 will oscillate the rock shaft 18 through the medium of the arm 42 and thereby actuate the 35 valve 19.

The valve 19 is normally arranged to close the flue 14 and in order to assist in thus positioning the valve, the end of the rock shaft 18 opposite the transverse arm 42 is formed 40 with a lateral arm 44, and upon this arm is adjustably mounted a weight 45.

In order to balance the lever 36 to a nicety, the end of the lever opposite the link 43 is provided with an adjustable weight 46.

45 In operation, when the temperature within the incubator rises above a predetermined amount, the stand rod 28 is elevated, and as above described, the rock shaft 24 will swing the finger 38, and this finger will in turn 50 actuate the balance lever 36. The lever 36 will, through the medium of the link 43 and arm 42 oscillate the rock shaft 18 to swing the valve 19 downwardly to close the air

pipe 15, and thereby cut off the hot air to the incubator. The hot air within the incubator can readily pass out through the air escape pipe 16 and thence through the flue 14. As soon, however, as the temperature within the incubator returns to its normal temperature, the thermostat 21 will permit 55 of the stand rod 28 to fall by gravity, and as a result, the parts will be returned to their normal position; that is, the valve 19 will be positioned to close the flue 14 and thereby permit the hot air from the burner 12 to 60 65 pass into the incubator through the pipe 15.

By means of the stand rod 28 having threaded engagement with the pin 27, the relative position between the stand and the thermostat 21 may be easily regulated, and 70 consequently the predetermined temperature within the incubator may be retained.

When it is desired to remove the top of the incubator, the sliding plate 33 is disengaged from the plate 31 and the head 32 of the rod 75 28 can then pass through the opening 29 of said top.

What is claimed is:

1. In a heat regulating system, the combination of a journaled shaft, a valve plate 80 carried by said shaft, a thermostat, a bar movable by said thermostat, a second journal shaft, a lateral arm on the first named shaft, a link connecting the free end of said arm and the second named shaft, and a rod 85 connected with said second named shaft and vertically adjustably connected with said bar.

2. In a heat regulating system, the combination of a journal shaft, a valve plate carried by said shaft, a thermostat, a bar movable by said thermostat, a rocker member pivoted upon said bar, the bar having screw threaded engagement with the pivot of said member, a second rock shaft, an arm carried by said 95 first named shaft, a link connected with the free end of said arm and said second named shaft, and a rock shaft revoluble in said member and connected with said second named rock shaft.

In testimony whereof, I affix my signature, in presence of two witnesses.

ADOLPH D. BREDER.
